Primary Examiner — Elizabeth J Oswecki*(74) Attorney, Agent, or Firm* — Senniger Powers LLP(57) **CLAIM**

The ornamental design for an artificial rose flower having metal petals, as shown and described.

DESCRIPTION

FIG. 1 is a front elevational view of a first embodiment of an artificial rose flower having metal petals, showing my new design;

FIG. 2 is a rear elevational view thereof;

FIG. 3 is a right elevational view thereof;

FIG. 4 is a left elevational view thereof;

FIG. 5 is a top plan view thereof;

FIG. 6 is a bottom plan view thereof;

FIG. 7 is a front elevational view of a second embodiment of an artificial rose having metal petals, showing my new design;

FIG. 8 is a rear elevational view thereof;

FIG. 9 is a right elevational view thereof;

FIG. 10 is a left elevational view thereof;

FIG. 11 is a top plan view thereof; and,

FIG. 12 is a bottom plan view thereof.

The broken lines in FIGS. 1 and 7 in the drawings indicate environmental structure which forms no part of the claimed design.
